UNITED STATES PATENT OFFICE

2,483,527

SHIPPING COOP

Ose F. Carpenter, Brightwood, Va.

Application October 14, 1946, Serial No. 703,179

1 Claim. (Cl. 217—56)

1

This invention relates to shipping coops for live poultry.

An object of this invention is to provide a coop of this kind including an improved means for securing and retaining the top closure so that the top closure will be able to withstand excessive weight without breaking.

Another object of this invention is to provide a shipping coop or crate which is formed with reinforcing longitudinal bars in the top wall thereof, the bars being mortised into the adjacent end bars and also including lower tongues engaging below the end bars so as to prevent splitting or breaking of the longitudinal bars at the ends thereof.

Another object of this invention is to provide a shipping coop or crate wherein the supporting strap for the open end of the closure is formed to engage the top dowels closely adjacent the pair of intermediate longitudinal bars so that these dowels will not be put under undue strain when weight is placed on the longitudinal bars.

Another object of this invention is to provide a supporting strap for the open end of the closure formed to engage the top dowels closely adjacent the pair of intermediate longitudinal bars, making it unnecessary to use rivets, nails or other means for fastening this supporting strap to the intermediate longitudinal bars and in this way saving both the cost of rivets and the time required for drilling and riveting.

With the above and other objects in view, my invention consists in the arrangement, combination and details of construction disclosed in the drawings and specification, and then more particularly pointed out in the appended claim.

In the drawings,

Figure 1 is a plan view, partly broken away and in section, of a shipping coop or crate for chickens or turkeys, constructed according to an embodiment of this invention,

Figure 2 is a fragmentary sectional view taken on the line 2—2 of Figure 1,

Figure 3 is a fragmentary sectional view taken on the line 3—3 of Figure 2,

Figure 4 is a fragmentary sectional view taken on the line 4—4 of Figure 2,

Figure 5 is a fragmentary sectional view taken on any one of the lines 5—5 of Figure 1.

Referring to the drawing, the numeral 10 designates generally a rectangular frame forming the top of a shipping coop or crate. The frame 10 is formed of longitudinal side members 11, and transverse end members 12. The connection

2

between the adjacent ends of the side and end members 11 and 12 respectively is preferably a mortise and tenon connection of conventional construction.

5 The frame 10 has disposed between the opposite members 11 thereof, a pair of longitudinal intermediate bars 13 and 14. The longitudinal bars 13 and 14 are connected at the opposite ends thereof to the end member 12 by a mortise and tenon connection or joint 15 and 16 as shown in Figure 2. The height of the bars 13 and 14 is substantially greater than the height of the end members 12, and as shown in Figure 2, the upper edges of the intermediate bars 13 and 14 are flush with the upper sides of the end members 12. A reinforcing tongue 17 is formed parallel with the tenon 16, and as shown in Figures 2 and 5, the tongue 17 is adapted to engage beneath the lower side of the end member 12 and serves as 10 a support for this end member, in addition to providing a reinforcing means to prevent the splitting or breaking of the intermediate bars when a weight is placed thereupon.

15 A plurality of elongated dowels 18 are extended through the intermediate bars 13 and 14 and are sealed at the opposite ends thereof in sockets provided in the side members 11. At a suitable point between the end members 11 and 12, there are formed short dowels 19 which extend 20 only between the side members 11 and the adjacent intermediate member 13 or 14, thereby providing an entrance opening 20.

25 A closure plate 21 is adapted to be disposed in the opening 20 and is rockably mounted on an elongated metal bar 22, which as shown in Figure 1, is sealed at the opposite ends thereof in sockets 23 formed in the side members 11. The closure 21 is spring-pressed to maintain this 30 closure in substantially contacting relation with the inner side of the intermediate bar 13, by means of a spring 24, which is disposed about the bar or pivot member 22 and is sealed at its inner end in a socket 25 formed in the adjacent edge of the closure 21. The closure 21 at the free end thereof is formed with a keeper or socket 26 within which a locking pin 27 is adapted to engage. The spring 24 normally holds the closure 21 in a locking position, and the closure may be 35 sealed in its locked position by means of a wire sealing means which may be extended through a hole 28 formed in the closure 21, and then wrapped about the intermediate bar 13.

The locking pin 27 is formed integral with one 40 of the short dowels designated 19a. This dowel

extends entirely through the intermediate bar 13, as shown in Figure 1, and projects beyond this intermediate bar so as to provide the locking pin.

In order to provide a means for supporting the free end of the closure 21 when in closed position, I have provided a transversely extending horizontal strap generally designated as 29. The strap 29 includes an upwardly offset intermediate portion 30 which is adapted to engage the lower side of the closure 21 and is disposed between the two intermediate bars 13 and 14. The strap 29 also includes downwardly and outwardly extending extensions 31, terminating in horizontal portions 32, engaging beneath the lower edges of the intermediate bars 13 and 14. The outer ends of the horizontal portions 32 terminate in upwardly extending right angular extensions 33 which are formed with holes 34 through which the adjacent short dowels 19 are adapted to extend. The upwardly extending outer portions 33 of the strap are adapted to snugly engage against the outer side of the intermediate bars, and by having the upward extensions bear against the short dowels 19a at the point where these dowels enter the intermediate bars, the strap 19 will not tend to place any undue breaking strain on the short dowels when undue weight is placed on the closure 21.

With a shipping coop or crate constructed as hereinbefore described, the top of the crate or coop will not break when undue weight such as the weight of a person is placed on the top of the crate. Furthermore, by providing the improved metal support bar for the free end of the closure, the closure will not split when weight is placed thereon as is the case where the closure is formed

with a rabbet or engagement over one of the dowels between the intermediate bars.

I do not mean to confine myself to the exact details of construction herein disclosed, but claim all variations falling within the purview of the appended claim.

What I claim is:

In a shipping coop having a top wall formed of a rectangular frame, dowels extending across the sides of the frame, and a pair of intermediate longitudinal bars between the ends of the frame each of said intermediate bars having a height greater than the height of said frame, the plane of the lower side of said bars being offset downwardly from the plane of the lower side of said frame; a closure pivotally disposed between said pair of bars, and a closure supporting strap fixed between said bars, said strap being formed with upturned apertured ends disposed on the outer sides of said longitudinal bars through which aligned dowels are adapted to engage for securing said strap on said coop, and said strap also including an upwardly offset intermediate portion upon which the lower side of said closure is adapted to engage.

OSE F. CARPENTER.
